UNITED STATES PATENT OFFICE.

JOHN W. GEARHART, OF FRESNO, CALIFORNIA.

LINE-MARKER.

1,159,014.

Specification of Letters Patent.

Patented Nov. 2, 1915.

Application filed September 22, 1914. Serial No. 862,962.

To all whom it may concern:

Be it known that I, JOHN W. GEARHART, a citizen of the United States, residing at Fresno, in the county of Fresno and State 5 of California, have invented new and useful Improvements in Line-Markers, of which the following is a specification.

The invention relates to a line marker for use in copying manuscript, printed matter, 10 stenographic ciphers, or the like.

The primary object of the invention is the provision of a marker of this character wherein the same can be supported and clamped to the pages of a memorandum 15 book to lie transversely of the exposed face of the uppermost page, and is capable of ready and easy adjustment to enable the user to observe with accuracy a particular line on said page during the act of copying.

Another object of the invention is the provision of a marker wherein the same can be held firmly on the memorandum book and is readily adaptable to books of varying widths, and which may be moved length- 25 wise of a page when the book is open to insure the reading of each line to be copied with certainty and accuracy.

A further object of the invention is the provision of a marker of this character 30 which is extremely simple in construction, readily and quickly mounted in position on and removed from a book, conveniently and easily adjusted relative to the lines on a given page therein, strong, yet light in 35 weight, durable, reliable and efficient in its purpose, and inexpensive in manufacture.

With these and other objects in view, the invention consists in the construction, combination and arrangement of parts as will be 40 hereinafter fully described, illustrated in the accompanying drawing, and pointed out in the claim hereunto appended.

In the drawing: Figure 1 is a perspective view of an open memorandum book showing 45 the marker constructed in accordance with the invention applied. Fig. 2 is a longitudinal sectional view through the marker. Fig. 3 is a vertical transverse sectional view. Fig. 4 is a side elevation.

Similar reference characters indicate corresponding parts throughout the several 50 views in the drawing.

Referring to the drawing in detail, A designates a memorandum or note book, which is of the usual well-known construction, 55 having therein the usual lined pages B, over the exposed face of a given one of which is adapted to traverse the marker C hereinafter fully described.

The marker comprises a base member 5 60 preferably made from metal, in the form of a strip having upwardly and inwardly bent guide flanges 6 which overhang the said base 5 and form a suitable guideway for the movable slide sections 7 of a clamp, 65 the outer ends of the said sections being formed with down-turned jaws or clamping ears 8 to engage the longer edges of the pages B at opposite sides of the book when the base 5 rests transversely across the ex- 70 posed face of the outermost page for the mounting of the marker thereon.

The sections 7 at their inner adjacent ends are integrally connected through the medium of a spiral resilient loop 9 which 75 tends to move the sections toward each other, yet permitting the same to spread under tension so that the jaws or ears 8 will frictionally bind the side edges of a series of the pages B of the book A, and this loop 80 also serves as a hand hold to permit the shifting of the marker longitudinally of the page to align with any one of the lines on the exposed face of the outermost or uppermost page, thereby enabling a person to 85 read a particular line with accuracy when in the act of copying from the book.

The flanges 6 overlie the sections 7 to guide the same in their sliding movement upon the base 5, the loop 9 being formed 90 with cut-away portions 10 to form a clearance for the flanges 6 so as not to bind or interfere with the movements of the sections, which are tensioned by the said loop.

From the foregoing description, taken in 95 connection with the accompanying drawing, it is thought that the construction and manner of use of the device will be clearly understood, and therefore a more extended explanation has been omitted.

100

What is claimed is:

A line marker of the class described comprising an elongated base of uniform width throughout its length and having guide

flanges at its longer edges, slidable sections mounted upon the base and engaged by the flanges, a resilient spirally formed loop integrally connecting the sections to hold the 5 same tensioned, and jaws at the outer ends of the sections without the said base.

In testimony whereof I, affix my signature in presence of two witnesses.

JOHN W. GEARHART.

Witnesses:

M. G. GALLAHER,

L. LA VAL.
